[57] CLAIM

[**] Term: 14 Years

The ornamental design for the trellis post, as shown and described.

[21] Appl. No.: 29/093,712

DESCRIPTION

[22] Filed: Sep. 17, 1998

FIG. 1 is a front perspective view of a trellis post embodying the present invention having two rows of apertures;

[51] LOC (7) Cl. 25-01

FIG. 2 is a rear perspective view of the trellis post shown in FIG. 1; and,

[52] U.S. Cl. D25/132

FIG. 3 is an end view of the trellis post shown in FIG. 1.

[58] Field of Search D25/126, 131,
D25/132; 40/606, 607, 608; 52/742, 732.3,
736.1, 726.3; 256/21-22, 34, DIG. 5, 65

The trellis post is symmetrical along its central axis and identical at its ends. The trellis post is shown in the Figures to be broken in the center to indicate indefinite length.
